ATTORNEY

UNITED STATES PATENT OFFICE

DAVID SEITZMAN, OF NEW YORK, N. Y.

AUTOMATIC ANTIHOLDUP DOOR CONTROL

Application filed December 11, 1931. Serial No. 580,313.

This invention relates to new and useful improvements in an automatic anti-holdup door.

The invention has for an object the construction of a device of the class mentioned which is characterized by the provision of door sections having adjacent edges at an inclination to the vertical to cause the sections to respectively move up and down when the doors are shut or when some article is placed therebetween.

As a still further object of this invention it is proposed to provide means for latching the door sections in closed position upon upward and downward motion respectively.

The invention has for a still further object the arrangement of a compartment enclosed by a pair of doors constructed and set forth so as to entrap holdup men between them.

It is a still further object of this invention to be able to operate either one of the pair of doors independently or simultaneously or to use only one of the pair of doors depending whether it is installed for use of banks, jewelry stores, or any other place where valuables are kept.

Furthermore, as another object, it is proposed to modify the invention with the construction of doors from more than two door sections.

The invention has for another object the construction of a device of the class described which is of simple, durable construction, dependable in use and efficient in operation, and which can be manufactured and sold at a reasonable cost.

For further comprehension of the invention and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a door frame with an automatic anti-holdup door constructed according to this invention.

Fig. 2 is a fragmentary horizontal section al view taken on the line 2—2 of Fig. 1.

Fig. 3 is a fragmentary vertical sectional view taken on the line 3—3 of Fig. 1.

Fig. 4 is a fragmentary vertical sectional view taken on the line 4—4 of Fig. 1.

Fig. 5 is a fragmentary vertical sectional view taken on the line 5—5 of Fig. 1.

Fig. 6 is a fragmentary vertical sectional view taken on the line 6—6 of Fig. 1.

Fig. 7 is a fragmentary vertical sectional view taken on the line 7—7 of Fig. 4.

Fig. 8 is a view similar to a portion of Fig. 1 but illustrating a modified arrangement.

The reference numeral 10 indicates a door frame in which there is a front wall 11 and a rear wall 12. In each of these walls there is mounted door sections 13 and 14 composing a door. These door sections are disposed in a vertical plane and mounted for horizontal sliding. They are resiliently supported at the tops and bottoms and have their adjacent edges 15 inclined to the vertical at an angle so as to cause one section to move up and the other down when the door is closed or when some object is clamped between the door. A lock 16 is mounted upon one of the door sections and is engageable with a keeper 17 on the other door section to lock the doors closed until it is opened from the outside with a key.

One of the door sections may be provided with a drawer 18. This drawer, as shown in Fig. 3, has its front and rear faces flush with the front and rear faces of the door section. Pegs 19 project from the sides of the drawer into recesses 20 formed in the door section so as to limit retraction and extension of the drawer. A spring 21 acts between the door section and the drawer to normally urge it closed. The drawer has its inner side slightly cut away, as indicated by numeral 22, and a portion of the door section is recessed, indicated by reference numeral 23, so as to allow a burglar entrapped behind the door to deposit his weapons within the drawer to surrender to guards outside.

The pair of door sections 13 and 14 may slide in any suitable channel or guide in a horizontal direction.

Suitable electrical or mechanical device may be provided for producing an oral sig-

nal when the door sections are operating.

A means is provided for opening and closing the door sections. This means is shown to comprise a rod 24 vertically through each of the door sections so that the door sections may slide up and down thereon and a rod extending through elongated slots 25 at the top and bottom of the door frame. Levers 26 are pivotally connected at one of their ends upon the rods 24 and at the other ends 27 are pivotally connected upon a stationary member. Intermediately, these levers connect with rods 28 movable by members 29. The details of the members 29 are not shown since they form no part of this invention. They may be pneumatic cylinders, solenoids, or the like. Similar constructions are generally known in the art.

The means for resiliently supporting the door sections comprises a plurality of springs 30 attached upon shoulder portions 31 on the door sections and acting against portions of the frame 10. These springs are located on the upper and lower edges of the door sections. These edges of the door sections are disposed within recesses 32 formed within the door frame. A rack of teeth 33 is attached on each of the door sections and is engageable with a complementary rack of teeth 34 attached upon the door frame. More particularly, the door section 13 has the racks 33 and 34 at the top while the door section 14 has these racks at the bottom. Consequently, when the door sections are moved together because of the inclined sides 15 they are caused to move correspondingly up and down and thus lock in position. The bottom edge of the door section 13 and the top edge of the door section 14 is disposed merely within a recess 35. There is no provision of shoulders, springs or racks as described relative to the other edges.

In Fig. 8, a modified arrangement of the invention has been disclosed in which the door is composed of more than two door sections. More particularly, these sections are indicated by reference numerals 13, 14 and a central section 36. The central section has its opposite sides parallel to each other and is merely slidable within the frame. The end sections 13 and 14 are constructed similar to the sections having corresponding numerals in the preferred form. Locks 16 are shown on the end sections engageable with keepers 17 on the center section. The center section is also shown equipped with the door 18.

The operation of the device consists in causing the door sections to close in an attempt to entrap the robber, holdup man, or burglar between the walls 11 and 12. Should the person attempt to stop the closing of the doors by inserting his foot or any other object between the door sections before they are

completely closed, the inclined edges 15 will cause the door sections to respectively raise and lower and latch them against opening. If no obstacles are placed between the door sections, they will completely close and automatically assume raised and lowered positions. When the form used in Fig. 8 is in operation, the central section 36 does not move up or down but just in end sections. The door operating mechanism may be controlled by push buttons or similar means located at various strategic points.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new, and desire to secure by United States Letters Patent is:—

1. In an automatic anti-holdup door, a frame, door sections horizontally slidably and resiliently supported and having end contacting edges at an inclination to cause one section to move up and the other down when the door sections are forced together or forced upon some article interposed, means for closing and opening said door sections, stationary racks upon said door frame above and below said door sections, and tooth members on said door sections engageable with said racks in the door sections and forced up and down respectively.

2. In an automatic anti-holdup door, a frame, door sections horizontally slidably and resiliently supported and having end contacting edges at an inclination to cause one section to move up and the other down when the door sections are forced together or forced upon some article interposed, means for closing and opening said door sections, stationary racks upon said door frame above and below said door sections, and tooth members on said door sections engageable with said racks in the door sections and forced up and down respectively, said frame having front and rear walls with a latch spaced therebetween so that a person may enter and be entrapped upon closing of the doors in said walls.

3. In an automatic anti-holdup door, a frame, door sections horizontally slidably and resiliently supported and having end contacting edges at an inclination to cause one section to move up and the other down when the door sections are forced together or forced upon some article interposed, means for closing and opening said door sections, stationary racks upon said door frame above and below said door sections, and tooth members on said door sections engageable with said racks in the door sections and forced up and down respectively, a means being provided for

latching said sections closed, comprising a lock upon one section engageable with a keeper on the other.

4. In an automatic anti-holdup door, a frame, door sections horizontally slidable and resiliently supported and having end contacting edges at an inclination to cause one section to move up and the other down when the door sections are forced together or forced upon some article interposed, means for closing and opening said door sections, stationary racks upon said door frame above and below said door sections, and tooth members on said door sections engageable with said racks in the door sections and forced up and down respectively, the upper and lower edges of said door sections engaging within recesses formed in the door frame, and springs being attached upon the door sections on the edges within the recesses and engaging the door frame for accomplishing the resilient holding of the door sections.

5. In an automatic anti-holdup door, a frame, door sections horizontally slidable and resiliently supported and having end contacting edges at an inclination to cause one section to move up and the other down when the door sections are forced together or forced upon some article interposed, means for closing and opening said door sections, stationary racks upon said door frame above and below said door sections, and tooth members on said door sections engageable with said racks in the door sections and forced up and down respectively, said door having an idler door section between either door sections and its opposite sides being parallel with each other and at an inclination to the vertical.

6. In an automatic anti-holdup door, a frame, door sections horizontally slidable and resiliently supported and having end contacting edges at an inclination to cause one section to move up and the other down when the door sections are forced together or forced upon some article interposed, means for closing and opening said door sections, stationary racks upon said door frame above and below said door sections, and tooth members on said door sections engageable with said racks in the door sections and forced up and down respectively, each of said door sections being slidably mounted upon a vertical rod, and said means for opening and closing the door sections being connected with said rod.

66. In testimony whereof I have affixed my signature.

DAVID SEITZMAN.
